(57) **CLAIM**

The ornamental design for a handheld medical information terminal, as shown and described.

DESCRIPTION

FIG. 1 is a top plan view of a handheld medical information terminal showing our new design;

FIG. 2 is a perspective view thereof;

FIG. 3 is another perspective view thereof showing the stylus detached from the handheld medical information terminal;

FIG. 4 is a bottom plan view thereof;

FIG. 5 is a left side view thereof;

FIG. 6 is a right side view thereof;

FIG. 7 is a rear plan view thereof; and,

FIG. 8 is a front plan view thereof.
